INVENTOR
Samuel Wiley
BY *W. N. Roach*
ATTORNEY

UNITED STATES PATENT OFFICE.

SAMUEL WILEY, OF METUCHEN, NEW JERSEY.

GRENADE.

Application filed July 21, 1924. Serial No. 727,332.

(GRANTED UNDER THE ACT OF MARCH 3, 1883; 22 STAT. L. 625.)

To all whom it may concern:

Be it known that I, SAMUEL WILEY, a citizen of the United States, and a resident of Metuchen, county of Middlesex, and State 5 of New Jersey, have invented an Improvement in Grenades, of which the following is a specification.

The invention described herein may be used by the Government, or any of its officers 10 or employees in prosecution of work for the Government, or by any other person in the United States, without payment to me of any royalty thereon, in accordance with the act of March 3, 1883.

15 The subject of this invention is a grenade.

My invention resides in the provision of a 20 grenade which may be used either as a hand or rifle grenade without alteration or manipulation of its parts. Such a combination obviates the necessity of manufacturing and carrying independent types of grenades and further permits each rifle bearer to employ the grenade in the most advantageous manner as the exigency of the occasion may 25 demand.

Further my improved grenade is decidedly meritorious in that when it is to be discharged from a rifle the safety pin is not withdrawn thereby adding greatly to the 30 safety of the personnel. Should the breech cap misfire from one cause or another, the grenade may be withdrawn from the rifle stock without danger of the lever becoming disengaged to arm the grenade.

35 Other and equally important objects and advantages of my invention are: to provide a fuse element of two cooperating parts adapted to move freely in any direction within the limits of inclined planes; to dispose in the fuse element a delay element 40 which is incapable of transmitting ignition to a relay element until the expiration of the delay time; to mount the fuse members with respect to each other and to the grenade so 45 that on impact ignition may be transmitted to the relay element; and, to provide a grenade which if not exploded will become a safe dud after the time train has been consumed.

50 To these and other ends, my invention consists in the construction, arrangement, and combination of elements, described herein-after and pointed out in the claims forming a part of this specification.

55 A practical embodiment of my invention

is illustrated in the accompanying drawings, in which,

Fig. 1 is a view in side elevation of my combination grenade;

Fig. 2 is a longitudinal sectional view; and 60

Fig. 3 is a plan view.

Referring to the drawings by numerals of reference:

A grenade body 10, scored to provide proper fragmentation, is open at one end to 65 threadedly receive a bouchon 11 having a central cylindrical wall 12 depended within the body to form when closed a chamber 12'.

The bouchon is formed with a transverse 70 passage 13, one end of which is reduced as at 14 and opens into a slot 15 formed in one side of the bouchon below the passage.

A striker 16 inserted in the passage is 75 formed with a flanged base 17, which is engaged by the hook end 18 of a lever 19 to hold the striker in cocked position against the tension of a spring 20 embracing the striker and confined between an enlarged head 21 formed thereon and an internal annular shoulder 22 formed by the reduced section 14 of the passage 13.

The lever is securely locked in this position by a split pin 23 passing through 85 aligned apertures 24 in extensions 25 of the bouchon thence through the lever 19 and into an opening 26 in the bouchon. A ring 27 within the head of the pin 23 is provided to facilitate removal of the pin to enable the striker to disengage itself from the lever. 90

Disposed in the opposite end of the passage 13 is a screw plug 28, which carries a primer 29 adapted to be primed by the striker 16 when the lever is released. The passage 13 is closed by a plug 30 which holds 95 the primer plug in place. The bouchon is formed with an extended portion 11', as best seen in plan in Figure 3, to accommodate the primer and closing plugs.

The bouchon is also provided with a passage 31 filled with powder 32 for relaying the flash from the primer to the center of the bouchon.

The bouchon includes an extension head 33, threaded to the circular wall 12 to form 105 a chamber 12'. The bouchon body 11 and the extension head 33 are formed with seats 34 and 35 in which are respectively mounted telescoping members in the form of an upper plunger 36 and a lower plunger 37. 110

The lower plunger is U-shaped in cross section and is adapted to receive the blade of the upper plunger which is T-shaped in section. Each of the plungers are constrained to be seated by reason of a powder pellet 38 disposed in the lower plunger and which is adapted to be ignited by a delay train 39 in the upper plunger which is in contact with the relay charge 32.

10 The lower plunger carries on its under face a circular time train 40, adapted to be ignited by the flash from the pellet 38 which passes through a port 41. As long as the lower plunger remains seated, the 15 flash from the time train cannot be transmitted to a relay charge 42 carried in the extension head 33. The time train 40 is in line with the perimeter of the seat 35 so that only a slight displacement of the 20 lower plunger will be necessary in order to cause ignition of the relay charge 42.

The plungers are engaged in a close sliding fit so that they will ordinarily not be moved together until impact of the grenade 25 unseats the lower plunger, thereby permitting the flame from the circular time train to pass to the relay charge 42.

The extension head 33 is formed with a groove 43 to retain a thimble 44 in which 30 is disposed a detonating charge 45 spaced from a powder pellet 46 in the extension by a centrally apertured cork plug 47.

The upper end of the bouchon is formed with a circular recess 48 adapted to frictionally retain a breech cap 49 in which is 35 carried a propellant charge 50. The breech cap is centrally depressed as at 51 to correspond to the shape of the firing mechanism in the discharger of the rifle. A percussion cap 52 carried by the breech cap is partially inserted in a guide 53 positioned in a depression in the bouchon and formed with ports 54 for an obvious purpose.

An L-shaped bracket 55 secured to the 45 breech cap and resting on the upper extension 25 is provided with an aperture to receive the split pin 23.

When the grenade is fired from a discharger, the explosion of the propellant 50 charge 50 expels the grenade, the breech cap and split pin remaining in the piece thereby allowing the lever to be disengaged from the striker the instant the grenade leaves the discharger.

55 When used as a hand grenade the split pin is manually removed and the grenade thrown in the usual manner.

The plungers are held in unarmed position until the pellet 38 is consumed but they 60 will remain in this position until impact, although now armed, by reason of their frictional engagement. The bouchon chamber 12 is of sufficient size to permit the plungers to be easily unseated on impact but only after the complete combustion of

the delay train 39 and the pellet 38. The detonator cannot be exploded unless the lower plunger is unseated and only then during the burning of the circular time train 40. The time train is designed to 70 prolong the period of ignition when the grenade is to be thrown to great distances. Should an explosion fail to occur after the burning of the time train, the grenade will be henceforth inoperative.

75 While in the foregoing there has been illustrated and described such combination and arrangement of elements as constitute the preferred embodiment of my invention, it is nevertheless desired to emphasize the 80 fact that interpretation of the invention should only be conclusive when made in the light of the subjoined claims.

I claim:

1. A combination hand and rifle grenade including a body, a bouchon for closing said body, a striker in the bouchon, a lever for holding the striker in cocked position, a pin for locking said lever, a breech cap carried by the bouchon, a propellant powder within the cap and a bracket secured to the cap for receiving the locking pin whereby the same is extracted from the lever when the propellant charge is exploded.

2. A combination hand and rifle grenade including a body, a bouchon for closing the body, a breech cap carried by the bouchon, and a propellant charge within the breech cap.

3. A combination hand and rifle grenade including a body, a closure for the body, a firing mechanism in the closure, a lever for holding the firing mechanism inoperative, a pin for locking the lever, a breech cap carried by the closure, and means for removing the locking pin as the grenade is propelled from a gun.

4. A grenade including a body, a bouchon for closing the body, said bouchon formed with a transverse passage and a slot in communication therewith, a striker in the passage, and a lever formed with a hooked end, the hooked end disposed in the slot and extending into the passage to hold the striker against tension.

5. A grenade including a body, a bouchon for closing the body, said bouchon provided with a chamber, relay charges axially carried by the bouchon at opposite sides of the chamber, seats formed on the bouchon and projecting into the chamber, cooperating plungers mounted in the seats, a delay train carried in one of said plungers and a combustible element carried in the other for normally preventing unseating of the plungers until the delay train is consumed, said plungers being further frictionally engaged to be held seated until impact.

6. A grenade including a body, a bouchon for closing the body, said bouchon provided

- with a chamber, the top and bottom walls of the chamber formed with concentric projecting seats, telescoping plungers mounted in the seats, a delay train in the upper 5 plunger, a combustible element in the lower plunger for preventing collapse of the plungers until the delay train is consumed, a time train carried in the under face of the lower plunger in line with the perimeter of the 10 lower seat, and relay charges in the bouchon axially of the plungers.
7. A grenade including a body, a bouchon for closing said body, cooperating members within the bouchon and normally inoperative until impact, a delay train carried by one member and a time train by the other, said time train adapted to prolong the period of ignition when the grenade is thrown to great distances.
- 15 8. A grenade including a body, a bouchon for closing the body, said bouchon provided with a chamber, telescoping members seated in the bouchon at opposite ends of the chamber, a delay train carried in one of said members, combustible means for preventing collapse of said members until the delay train is consumed, said members being further frictionally engaged to be held seated until impact.
- 20 9. A grenade including a body, a bouchon for closing the body, said bouchon provided with a chamber, relay charges carried by the bouchon at opposite sides of the chamber, and cooperating members releasably held between said relay charges for transmitting ignition on impact.
10. A grenade including a body, a bouchon for closing the body, said bouchon provided with a chamber, relay charges carried by the bouchon at opposite sides of the chamber, 40 members releasably held between said relay charges, means for transmitting ignition carried by said members, one of said means adapted to normally retain said members in unarmed position.
- 45 11. A grenade including a body, a bouchon for closing the body, said bouchon provided with a chamber, relay charges carried by the bouchon at opposite sides of the chamber, and means releasably held between said 50 relay charges for transmitting ignition.
12. A projectile, a firing mechanism therein, a propellant case on the projectile and a safety member secured exteriorly to the case for preventing actuation of the firing mechanism.
- 55 13. A projectile, a firing mechanism therein, a propellant case on the projectile and a safety member secured to the case for preventing actuation of the firing mechanism.
- 60 14. In fixed ammunition, a projectile, a firing mechanism therein, a safety member for preventing actuation of the firing mechanism, and a propellant case adapted to control release of the safety member.
- 65 15. A projectile including a firing mechanism, a longitudinally disposed safety pin for said mechanism, and means whereby said pin is retained as the projectile is expelled from a gun.

SAMUEL WILEY.
